A. C. BROWNELL, OF BROOKLYN, NEW YORK.

Letters Patent No. 91,903, dated June 29, 1869.

IMPROVEMENT IN THE CONSTRUCTION OF SHEET-METAL BOILERS.

The Schedule referred to in these Letters Patent and making part of the same.

To all whom it may concern:

Be it known that I, A. C. BROWNELL, of Brooklyn, Kings county, New York, have invented a new and useful Improvement in Copper Water-Boilers; and I do hereby declare that the following is a full, clear, and exact description thereof, which will enable others skilled in the art to make and use the same, reference being had to the accompanying drawings, forming part of this specification.

Figure 1 is a side view of my improved boiler, completed, parts being broken away to show the construction.

Figure 2 is a longitudinal section of a part of the same, partially formed, illustrating the manner of construction.

Figure 3 is a cross-section of the same, taken through the line xz , fig. 2.

Similar letters of reference indicate corresponding parts.

My invention relates to water-boilers, or distributing-reservoirs, and has for its object to improve the construction of the same.

It consists principally in forming both heads dome-shaped, and securing them to the body by double-seaming, riveting, or brazing.

To accomplish this object, the body is divided into two halves, transversely, and the dome-heads double-seamed, riveted, or brazed thereto, respectively. These two halves are then double-seamed together, by introducing a ring, or band, to serve as a mandrel within one of the heads, and forming the seam over the same.

The mandrel, or ring remains within the boiler, and serves to strengthen the boiler and prevent its collapsing.

Heretofore, boilers have been made with one head double-seamed, but it has been found impossible to unite two dome-heads to the body in this manner, because, after double-seaming one head to the body, there are no means for introducing a mandrel within the boiler, upon which mandrel the double seam must be formed. The second head was therefore applied in a flat form, without double seaming, and frequently would be pressed from the body by the weight of the water within the boiler.

The invention also consists in beading the double seams of the heads longitudinally, in such a manner that the seam shall form part of the bead, thereby strengthening the latter, and imparting a neat and finished appearance thereto.

The seam is, as it were, swallowed up in the bead, and the point of connection nearly or entirely hidden from observation.

It has heretofore been customary to bead the body of a boiler at right angles to the seam, the latter ex-

tending longitudinally of the body, to unite its two sides to form a cylinder, but this beading forms simply an ornament for the heads, without affecting that portion of the seam lying between the heads. It serves simply as an ornament, and produces no strengthening effect whatever upon the seam.

A is the body of the boiler, to the end-edges of which the edges of the dome-shaped heads B are secured, by double seams, as shown in fig. 2.

The parts of the boiler in which the said seams are formed are then beaded, as shown in fig. 1, which beading, a^1 , not only strengthens the boiler, but also presses down the seam so that it is no longer discernible.

To enable this to be done, I make the body A, of the boiler in two parts, the line of division being at or near its centre.

The edge of the one part is then bent out at right angles, and the edge of the other part is bent twice at right angles, as shown in fig. 2, preparatory to double-seaming the said parts together.

A strong iron wheel, or band, C, is then inserted in the one part, in such a way as to support the edges of the two parts when put together, and serve as a mandrel in forming the double seam, by which said edges are connected to each other.

The wheel C may be made with cross-bars, or spokes, c' , as shown in fig. 3, or it may be made so heavy as not to require such strengthening. The seams may then be sweated and soldered, and the middle seam may be covered with a ring-cap, a^2 , neatly soldered to the sides of the body A, as shown in fig. 1, so as to give to said band the appearance of beading, as shown.

By this construction, I am able to produce a distributing hot-water boiler with a dome-head upon each end, and double-seamed together in all its parts.

This construction also enables the heads of the boiler to be secured to the body by riveting or by brazing.

The usual ingress, egress, and circulating-pipes are connected with the boiler in the ordinary manner.

I claim as new, and desire to secure by Letters Patent—

1. The improved water-boiler, with both heads dome-shaped, double-seamed, brazed, or riveted to the ends of its body, either with or without beading, substantially as herein shown and described, for the purpose specified.

2. The body of a hot-water boiler, made in two parts, double-seamed to each other, and double-seamed, brazed, or riveted to the dome-heads, substantially as herein shown and described, for the purpose specified.

3. The heavy wheel, or band, C, whether made with or without spokes, or cross-bars, in combination with the body A, of the boiler, at the point where the parts of said body are seamed to each other, substantially as herein shown and described, and for the purpose set forth.

4. Beading sheet-metal boilers, and other articles, longitudinally with the double seams, including the same, by which the parts of said articles are secured to

each other, substantially in the manner herein shown and described, and for the purpose set forth.

The above specification of my invention signed by me, this 15th day of February, 1869.

A. C. BROWNELL.
